Act 2.

UNITED STATES PATENT OFFICE

CLARENCE A. STEERE, OF PROVIDENCE, RHODE ISLAND, ASSIGNOR TO HOPE WEBBING COMPANY, OF PAWTUCKET, RHODE ISLAND, A CORPORATION OF RHODE ISLAND.

WARPING-MACHINE.

946,164.

Specification of Letters Patent. Patented Jan. 11, 1910.

Application filed May 5, 1909. Serial No. 494,170.

To all whom it may concern:

Be it known that I, CLARENCE A. STEERE, a citizen of the United States, residing at Providence, in the county of Providence 5 and State of Rhode Island, have invented certain new and useful Improvements in Warping-Machines, of which the following is a specification.

My invention relates to warping-machines, so-called, and it consists in certain novel devices associated with and forming a component part thereof, all as more fully hereinafter set forth and claimed.

The object sought to be attained is to 15 greatly increase the efficiency and output capacity of warping-machines. That is to say, to position and mount the cops and guide the several threads leading therefrom to the warp-beam on which they are to be 20 wound so that the threads will readily render to draw off from the cops with much greater rapidity and a more uniform degree of tension and at the same time with less liability of breaking, as compared with 25 warping-machines heretofore devised.

Among the devices employed in my improved warping-machine to accomplish the advantages just referred to are the following: to provide readily manipulated means 30 for removably securing the cop non-revolably and horizontally upon an arbor or cop-holder, thereby adapting the thread to be drawn from the free end of the cop; means adapted for removably securing the arbor 35 to a standard or frame; a checking or braking device to prevent the thread from being drawn too freely from the cop, while at the same time subjecting it to a proper degree of tension, and guides adapted to prevent 40 the threads of adjacent cops from excessive "ballooning" and interference with one another while they are being rapidly drawn from the outer or free end of the thus held stationary cops.

In the accompanying sheet of drawings, 45 Figure 1 represents a front end elevation of a warping-machine embodying my improvements. Fig. 2 is a horizontal or plan sectional view taken on line $\alpha - \alpha$ of Fig. 1. Fig. 3 is a partial plan view of the warp-beam, somewhat enlarged, showing a series 50 of cop-threads connected therewith. Fig. 4 is a partial front elevation, partly in section and in enlarged scale, showing the combined 55 brake and tension device for controlling the

thread. Fig. 5 is a horizontal sectional view of the cop-supporting frame or standard showing a cop-holder mounted therein, the cop itself being omitted. Fig. 6 is a partial side elevation of the said frame member, as adapted to receive the cop-holder. Fig. 7 is a detached plan view of the arbor or cop-holder, and Fig. 8 is a central longitudinal sectional view, enlarged scale, taken through the outer end portion of the arbor. 60 65

I would state in advance that the main winding mechanism proper of the warping-machine A, represented in Fig. 1 of the drawings, is well-known and I therefore make no claim to the same, except as combined with certain elements or devices hereinafter described. The said machine is provided with a reed b through which the segregated threads t are simultaneously drawn from the stationary cops and wound in the 70 usual manner upon the barrel of a revolute beam or flanged spool a .

B, designates a vertical stationary cop-supporting frame comprising the tubular post or pipe p and the tension-supporting 75 member d . The post member is provided throughout its length with a series of uniformly spaced horizontally disposed parallel holes p^1 , Fig. 6, each adapted to receive the hollow stem or shank e of the cop-holding 80 arbor E; the latter having a handle part e^1 , a collar e^2 at the base of the handle, and a fixed pin e^3 . This pin passes transversely through the shank and projects therebeyond, as represented in Fig. 5. Said pin is located 85 with relation to the collar so that when the shank is inserted to its limit in the corresponding hole p^1 of the hollow post, as determined by said collar, and the arbor turned axially about 90° the ends of the pin will 90 then engage or wedge themselves against the adjacent inner concave surface of the post's wall and cause the collar to bear snugly against the outer side of the post thereby firmly locking the arbor in position. It may 95 be added that slots p^2 , Fig. 6, extend from the pole p^1 in opposite directions through the wall to permit the free passage of the pin e^3 . The inner or free end portion of the hollow arbor is provided with a pair of 100 oppositely disposed narrow longitudinally extending slots e^4 and a fixed transverse pin r . Upon the latter is mounted a length of 105 helically wound resilient wire s having its free end portions bent to form crossed arms 110

⁵ which extend rearwardly within the arbor, as clearly shown in Fig. 8. The said arm members are further bent to serve as springs ¹⁰ *s*², adapted to normally extend through the respective slots *e*⁴. As thus devised the springs readily yield during the introduction of the arbor into the post and immediately thereafter return to the expanded or normal position. After the arbor is locked ¹⁵ in place as before described, it remains practically rigid so that the cop *c* may be readily mounted thereon, assuming that the bore of its quill or tube is the same or slightly greater than the diameter of the arbor, the pressure of the springs then causing the latter to frictionally bear against the quill and hold the cop stationary thereon, thereby preventing both endwise and axial movement.

Each thread *t* passes from the free end of ²⁰ its stationary horizontally mounted cop *c* to and between a pair of laterally separated light vertical guide-wires *c*³ to a device, *D*, adapted for controlling the tension and also for preventing a too free unwinding of the ²⁵ thread; the latter then passes through a fixed guide-eye *i* and the reed *b* and is wound upon the revoluble beam *a*.

The device, *D*, is supported by a horizontal bracket *d*⁴, in turn secured to the said ³⁰ upright member *d*, see Fig. 4. A fixed stud *d*² extends upward from the inner or free end of the bracket and is provided with a loose bottom washer *w*. A thin flat sheet-metal freely revoluble disk *h*, resting upon ³⁵ the washer, has an annular central hub *h*² on its upper side through which the stud *d*² projects. Upon said disk rests a flat revoluble fellow disk member *h*¹ having the said hub extending through it. The adjacent ⁴⁰ faces of the disks are maintained in normally light frictional contact with each other by means of the expansive force of a suitable superposed spring *g*. The outer edges or rims of the disks may be curved in opposite directions, as indicated at *f*, so as to form ⁴⁵ a continuous flaring entrance for readily guiding the thread between the disks. As thus constructed the free movements of the traveling thread passing from the stationary cop is or may be checked or retarded to some extent while it is being drawn between the disks by the revolving beam, thereby at the same time equalizing the tension upon the thread, and also serving to remove from it ⁵⁰ any loose fibers or light foreign matter. I deem it advisable to so guide the thread that when in use it will draw against the periphery of the adjacent portion of the hub, *h*², and cause both disks to rotate, although ⁵⁵ not necessarily in unison with each other.

Located in front of the free ends of the cops are positioned two parallel laterally separated vertical rods, *c*¹, *c*¹, the distance between them exceeding say the diameter of ⁶⁰ a full or loaded cop *c*; these rods and the

light vertically spaced horizontal wires *c*² connected to them and located between the cops, see Figs. 1, 2 and 4, serve when the machine is in action to prevent the traveling threads from excessive "ballooning".

The cops are first mounted and frictionally held stationary upon the previously positioned arbors *E*, as before described, and the free ends of the threads passed between the vertical guide-wires *c*³, followed by introducing the threads between the disks of the respective devices *D* and into the corresponding stationary guide-eyes *i*, Fig. 2; from the latter the threads extend in a converging manner to the usual reed *b* and onto the barrel of the winding beam *a*.

I claim as my invention and desire to secure by United States Letters Patent,—

1. In a warping-machine, the combination with a metal post having annular walls ⁸⁵ and a series of suitably spaced holes extending transversely therethrough, of a shoudered cop-holder having a shank or arbor adapted when in use to be seated in said hole and extend beyond the post, and a pin or lug integral with the arbor adapted upon turning the holder a partial revolution to engage the adjacent inner surface of the wall in a wedge-like manner for locking the holder in position.

2. In a warping machine, the combination of a vertical stationary frame, a plurality of relatively stationary cop-holders arranged above one another in horizontal planes removably seated in said frames, a ¹⁰⁰ combined thread-retarding and tension device located forwardly of each cop-holder and being in substantial alinement with its axis, a pair of laterally separated stationary vertical guide members located between the ¹⁰⁵ forward end of the cop-holders and said tension devices adapted when in use to lead the respective threads into the latter, and means for winding the threads upon a beam.

3. In a warping-machine provided with ¹¹⁰ a vertical post or standard and a plurality of normally stationary horizontally disposed cop-holders removably seated therein, the combination therewith of a pair of stationary laterally separated vertical guide-rods ¹¹⁵ located forwardly of the free ends of said holders, a plurality of stationary horizontal guide members spaced and arranged above one another and located intermediate said guide-rods and cop-holders, and tension devices adapted when in use to receive therein threads passing from cops mounted on said holders, the threads first passing between the said horizontal and vertical guide members.

4. In a warping-machine, the combination with a normally stationary horizontally mounted holder adapted to support a cop non-revolubly thereon, of a tension device positioned forward of the free end of the holder, said device consisting of a pair of supported flat ¹²⁵ ¹³⁰

disk-like members adapted for rotation disposed one above the other, the lower disk member having an upwardly extending hub passing through the upper or fellow disk, a 5 spring pressing upon the latter, and suitably located fixed guides, arranged when in use for directing a thread from the cop to and between the adjacent faces of the disks and also for conducting it from the latter 10 while it is being wound upon a spool or beam.

5. In a warping-machine, a cop-holder adapted to be removably seated in an apertured post or standard, said holder having

a spring element mounted interiorly there- 15 in provided with a pair of rearwardly extending oppositely arranged resilient crossed arms, each arm having a portion thereof normally projecting laterally through the shank or stem part of the holder, adapted 20 when in use to press against the bore of the cop to hold it in position thereon.

In testimony whereof I have affixed my signature, in presence of two witnesses.

CLARENCE A. STEERE.
